UNITED STATES PATENT OFFICE

95,383

DESIGN FOR A SHOE

Joseph Sofranksy, New York, N. Y.

Application December 3, 1934, Serial No. 54,238

Term of patent 3½ years

To all whom it may concern:

Be it known that I, Joseph Sofranksy, a citizen of the United States, residing in New York, in the county of New York and State of New York, have invented a new, original, and ornamental Design for a Shoe, of which the following is a specification, reference being had to the accompanying drawing, forming part thereof.

Figure 1 is a plan view of a shoe, showing my new design.

Figure 2 is a side perspective view of the shoe.

The dominant feature of the present design is the ornamental effect obtained by the strips inserted parallel and adjacent to each side of the lacing collar and extending from the upper edge of the shoe to points near the bottom of the lacing collar, the strips having rectangular openings.

I claim:

The ornamental design for a shoe, as shown and described.

JOSEPH SOFRANSKY.
